WIRE STAPLE FORMER AND STAPLING APPARATUS

Hans O. Irmscher, East Hempstead, Long Island, N. Y., assignor to National Urn Bag Co., Inc., Long Island City, N. Y., a corporation of New York

Application May 13, 1943, Serial No. 486,785

7 Claims. (Cl. 1-2)

1

This invention relates to the manufacture of staples from wire strands and the application thereof as fasteners or other like purposes. More particularly the invention is directed to an apparatus for converting a continuous wire of a bendable material, such as drawn metals of steel, copper, aluminum, bronze or of other suitable composition into staples and applying same in situ as fastener means.

Among the objects of the invention is to generally improve apparatus of the character described which shall comprise few and simple parts that are readily assembled to form a relatively small compact device which can be conveniently incorporated in machine constructions or combined with other mechanisms for various purposes, which shall be cheap to manufacture, which shall operate smoothly and reliably at a high output capacity, which shall require a minimum of attention in operation and maintenance, and which shall be practical and efficient to a high degree in use.

Other objects of this invention will in part be obvious and in part hereinafter pointed out.

This invention accordingly consists in the features of construction, combination of elements and arrangements of parts which will be exemplified in the construction hereinafter described and of which the scope of the application will be indicated in the following claims.

In the accompanying drawings, in which is shown one possible illustrative embodiment of the invention:

Figs. 1 and 2 are front elevational and top plan views, respectively, of a wire staple former and stapling apparatus constructed to embody the invention with the parts shown in open position to receive sheet material, strands or the like (not shown) to be fastened together by a formed staple in the well understood manner.

Figs. 3, 4 and 5 are cross-sectional views taken on lines 3-3, 4-4 and 5-5 in Fig. 1, respectively, Figs. 3 and 5 showing the interior construction of the wire feeding and rolling apparatus portions, and the relation of the latter to the cylinder cam control, and Fig. 4 showing an end view of said wire feeding and rolling portion, cylinder cam, and head die.

Fig. 6 is an enlarged sectional view as seen along line 6-6 in Fig. 4 showing the interior construction of staple forming portions, head die and the connections to the control cam.

Fig. 7 is an enlarged sectional view taken through the cylinder cam on lines 7-7 in Fig. 2.

Fig. 8 is view showing the development of the several continuous grooves of the cylinder cam shown in Fig. 7 in which rollers ride for the actuating slide members and lever of the controlled moveable parts of the wire feeding, staple forming and stapling apparatus portions.

2

Fig. 9 is a cross-sectional view as seen along lines 9-9 in Fig. 5 showing interior construction of the wire feeding and drawing portions and a top view jaw head and head die.

5 Figs. 9-A and 9-B are sectional views of the staple wire stock before and after, respectively, passing through the improved stapling apparatus.

Fig. 10 is an enlarged cross-sectional view as seen along lines 10-10 in Fig. 9 showing portion 10 of the staple forming construction.

Fig. 11 is a fragmentary sectional view showing portion of the improved apparatus with a formed staple in position to be applied as fastening means.

15 Fig. 12 is a cross-sectional view taken on lines 12-12 in Fig. 11 showing the position of the parts at the beginning of the staple driving operation.

20 Figs. 13 and 14 are enlarged fragmentary sectional views showing successive steps in clinching a formed staple as shown in Figs. 11 and 12 and applied as means for fastening a tag to the end of a string, and

Fig. 15 is a front elevational view of a tag 25 anchored to the end of a string by stapling with the improved apparatus embodying the invention.

Referring in detail to the drawing, 20 denotes a combination wire staple former and stapling apparatus constructed to embody the invention. Said embodiment is adapted to anchor by means of a metallic wire drawn staple S, a paper tag T to the end of a string or cord C, as shown in Fig. 15. It is to be understood that the improved apparatus 20 can be utilized to fasten together 35 or anchor sheet materials, strands or the like, for numerous purposes and various requirements.

As seen from Figs. 1 to 5, inclusive, and 7, a constant rotative power for apparatus 20 may be supplied from any suitable source (not shown) in 40 the well understood manner to a main drive-shaft 21 which is journaled between spaced bearings blocks 22a extending from a suitable base frame 22, the latter having firmly fastened thereto by screws 23a, a backing plate 23.

45 Said shaft 21 has mounted to turn therewith a cylinder type cam 25, secured by suitable means such as set screw 21a, shown in Fig. 7. Said cam 25 has cut into the curved surface thereof four spaced continuous grooves 25a, 25b, 25c and 50 25d which conform to the pattern layout P shown as a diagrammatic development in Fig. 8, as required for the various movements of the parts of apparatus 20 hereinafter described.

As seen from Figs. 1, 2 and 9 a suitably drawn 55 wire or strand W is continuously supplied from a suitable source, such as a reel (not shown) in the well understood manner through a guiding conduit 27 so as to pass between a pair of rolling wheels 28 and 29. In the passage of the wire W 60 between said wheels 28 and 29, the stock of said

wire W may be changed in cross-sectional shape from a circular as shown in Fig. 9—A to a flattened shape S, as shown in Fig. 9—B. The wheels 28 and 29 in gripping the wire W turn on shafts 28a and 29a, respectively, said wheels 28 and 29 being secured to underlying sides of meshed gears 28b and 29b, respectively, as shown in Figs. 2 and 5.

Said gears 28b and 29b are loosely intermeshed so that space between wheels 28 and 29 may be 10 adjusted for limited separation. To this end the shaft 29a, as shown in Fig. 5 is pivotably mounted at a lower end 29c thereof to an extension piece 32a projecting from an end of an elongated slide member 32 which is mounted to reciprocate in a slideway 22b on the frame 22 between the backing plate 23 and the cylinder cam 25. Said extension piece 32a also has the lower end 28n of shaft 28a bolted thereto. A desired adjustment setting of the spacing of wheels 28 and 29 is provided through a yoke member 33 pivoted at 33a on a headed upper end 28c of shaft 28a at a spaced distance from said extension piece 32a. Said yoke member 33 has fitted therein a threaded space adjuster stop 33b against which the upper free end 29d of shaft 29a is releasably retained by a knurl-headed finger screw 33c, as shown in Figs. 2 and 5. The threaded adjuster stop 33b may be secured in position by a set screw 33d. It is thus seen that the spacing of wheels 28 and 29 can be varied within limits by loosening the finger screw 33c, swinging yoke member 33 on pivot 33a to permit setting the threaded adjuster stop 33b and then refastening said finger screw 33c after reseating said yoke member 33.

As shown in Figs. 1 and 3, there is mounted against the under side of gear 28b to turn therewith a ratchet wheel 28d. A coiled spring-pressed pawl 28e mounted to pivot on a pin 28f carried at the free end of a lever 28g cooperates with ratchet wheel 28d. The other end of lever 28g may trunnion on shaft 28h held by a bracket portion 23b extending from backing plate 23, as shown in Figs. 1 and 3. A link 28j connects a mid portion of lever 28g with extension piece 32a through pivot pins 28k and 28m carried on said lever 28g and extension piece 32a, respectively. As said extension piece 32a is reciprocated with slide member 32, lever 28g swings on trunnion shaft 28h and the movement thereof causes the pawl 28e to engage with the ratchet wheel 28d for intermittently turning the gear 28b and the meshing gear 29b to roll the wire W passing from conduit 27 between wheels 28 and 29. The rolled wire S then passes through a curved conduit 27a and into a staple forming portion 20a of apparatus 20, said conduits 27 and 27a being secured by screw fastening means 27b on spaced arms 32f upstanding from extension piece 32a and moving therewith.

The headed upper end 28c on shaft 28a carries thereon spaced from pivot 33a, a lever 37 terminating in a finger stop end 37a, said lever 37 being pivotably mounted on a stud shaft 37b to extend said lever 37 in alignment with the direction of travel of slideway 22b. Said lever 37 is positioned on shaft 37b between adjustable spacing collars 37c and 37d, and is pressed down by a flat spring 37e carried by collar 37c as shown in Figs. 2 and 6. Lever stop end 37a serves to engage the mid portion of each staple S so as to clamp the same when forming, as shown in Figs. 11 and 12. The lever 37 cooperates with the staple forming portion 20a of apparatus 20 which is

mounted on the leading end of said slide member 32, and forms a movable unit with the wire feeding and rolling mechanism above described carried on extension piece 32a of slide member 32.

As seen in Figs. 10 to 14, the staple former portion 20a includes a head die 35 having a cover plate 35c secured by screws 35d, said head die 35 communicating through a groove 35a with conduit 27a for the passage of the rolled wire stock S therethrough. A central plunger or setter 38a, hereinafter referred to also as settor, flanked along opposite longitudinal edges by a pair of spaced end bender-cutters 36a extend through said head die 35 under the cover plate 35c, said bender-cutters 36a having one end of said pair secured on a cross-head 36b which has a clamp strap 36c fastened by screws 36d, the other end of said pair extending to ride in tracks 35b provided in head die 35 under said cover plate 35c, as shown in Figs. 4 and 10. The setter 38a slidably passes through the cross-head 36b and is secured by one end thereof on a cross-head 38b by a clamp strap 38c which is retained by a pin and screw 38d, as shown in Fig. 6.

The cross-heads 36b and 38b terminate slide members 36 and 38, respectively, said members being constructed with head die 35 of the staple forming portion 20a, cross-head 36b and cross-head 38b arranged in tandem relation in the plane of movement of slide member 32, as shown in Figs. 6 and 12. Said slide members 32, 36 and 38 may be assembled in superimposed or overlying positions and are mounted for independent sliding movement in slideway 22b, and mounted on inner ends of said slide members 32, 36 and 38, are suitable cam rollers 32e, 36e and 38e, respectively, which ride in grooves 25b, 25c and 25d, respectively, of the cam 25, as shown in Figs. 3 and 6.

Aligning and outwardly spaced from the die head 35, a suitable fixed jaw head 40 is provided, said jaw head 40 being seated to terminate the end 41a of a rigidly mounted J-shaped arm 41. Spaced pins 23d upstanding from frame 23 and a finger screw 41b releasably secure said arm 41 rigidly in position as shown in Figs. 1 and 2. A slideway 40a extends through the jaw head 40 and has a staple prong clincher presser member 42 slidably mounted to reciprocate therein. Said presser member 42 may be supported by a suitable screw adjusting mounting 42e from an end of a slide rod 42b which is mounted for movement on arm 41.

Said slide rod 42b may be retained by spaced screw and slot connection 42c to said arm 41 and through a pivot pin 42f connects with a mid portion of a lever 42d. The outer end of said lever 42d may pivot on a screw 43a that extends up from a rigidly mounted extension plate 43, the latter being secured to the frame 22 by a spaced pin and screw fastening means 23e. The inner end of said lever 42d extends over the cam 25 and carries a roller 42g which rides in cam groove 25a, as shown in Figs. 2 and 7.

It is desirable that a casing cover 44 secured by screws 44a be provided, said cover 44 with the bearing blocks 22a of the base frame 22 forming a housing to enclose the cylindrical cam 25 and the operating parts extending therefrom.

The various parts of apparatus 20 which are constructed and assembled to move in timed relation are controlled by through cam 25, a development of which may be as shown at P in Fig. 8.

From the above described parts of apparatus

20 assembled as shown in the drawings, the operation will be apparent.

The drawn wire W is inserted into conduits 27 and 27a and between the rollers 28 and 29 with the finger screw 33c loose. On tightening said screw 33c the two rollers 28 and 29 will be brought into desired, spaced relation for rolling the wire W from a circular cross-sectional shape to a flattened shape, as is shown in Figs. 9—A and 9—B, respectively. By providing a suitable power drive to shaft 21 the cylindrical cam 25 will be rotated and slide members 32, 36 and 38 and lever 42 will be moved through the action of the rollers 32e, 36e, 38e and 42e riding in cam grooves 25a, 25b, 25c and 25d, respectively. If then articles such as the tag T and string or cord C are to be stapled, the die head 35 may be provided with a suitable edge groove for seating the cord C with the tag T retained by any suitable means against the die head 35 while the slide member 32 is retracted to its extreme inwardly moved position for separating the jaw head 40 from the die head 35, as shown in Figs. 3 and 9. In Fig. 3 the dotted line position shown of slide member 32 is its extreme outwardly moved position.

When the leading end of wire S reaches the position to occupy and extend through groove 35a in the staple forming portion 20a with the die head 35 separate from the jaw head 40 and the tag T and cord C inserted therebetween, as described above, the finger stop end 31a of lever 36 is positioned as shown in Figs. 6 and 9. Now on rotation of the power drive shaft 21, the cam 25 through movement of slide members 36 and 38 will first cause the bender-cutters 36a and setter 38a, respectively, to move into the position shown in Fig. 11 for cutting off a portion of wire S and bending and piercing prongs thereon to provide a U-shaped structure. The head die 35 through the movement of slide member 32 will move to clamp the tag T and cord C firmly between said die head 35 and jaw head 40, as shown in Fig. 11.

As the cam 25 continues to rotate, the presser member 42 through said lever 42d and slide rod 42b is forced against the prongs of the bent U-shaped staple, which in the movement of the die head 35 and jaw head 40 have already caused the prongs to simultaneously pierce the tag T 50 and then deflect said prongs toward each other by tapered guide portions 40b terminating slideway 40a of jaw member 40. The prongs of staple S will finally be clinched to firmly anchor the tag T to the cord C, as is clear from the successive steps shown in Figs. 11, 13 and 14.

Each rotation of the cam 25 through the movement of roller 32e in cam groove 25b reciprocates the slide member 32 with the extension 32a and, as has already been described, will intermittently 60 turn the rollers 28 and 29 through the meshed gears 28b and 29b, respectively, and the combined turning movement of the ratchet wheel 28d by the pawl 28e and the rectilinear motion of the unit carried by slide extension 32a. This above 65 described operation not only rolls the wire W but also is feeding the same to the staple forming portion 20a and serves to draw the wire W from the supply source.

By providing movable presser member 42 reciprocated through the slide rod 42b and lever 42d in timed relation by means of the movement of roller 42g in cam groove 25a, positive clinching of the deflected staple prongs is effected with the application of a minimum degree of 70 75

pressure force. It should be noted that presser member 42 is so arranged and constructed to be extended in operation beyond the tapered guide portion 40b, as shown in Figs. 1 and 9, so that should no material be inserted between the jaw head 40 and the die head 35, any clinched or loose staples S formed will be ejected and thereby prevent clogging or other defective operations.

10 Extremely high operating speed is made possible with apparatus 20 because of the arrangement and construction of the parts above described which provide that the forcing of the U-bent staple structure S through the material, such as tag T and cord C, and finally clinching same takes less than one twelfth the time of a complete cycle of operation, comprising one revolution of the cam 25. The remaining eleven twelfths of the cycle can be utilized to move the material T and C to be stapled in and out of clamped position between the head die 35 and jaw head 40. It should be noted that the roller 42g in cam groove 25a which controls the movement of presser member 42 through slide rod 42g is arranged to be 90° in advance of the other cam roller movements which must be taken into consideration when calculating the above timing from the cam development shown in Fig. 8.

It is thus seen that there is provided an apparatus in which the several objects of this invention are achieved and which are well adapted to meet the conditions of practical use.

As various possible embodiments might be made of the above invention, and as various changes might be made in the embodiment above set forth, it is to be understood that all matters herein set forth or shown in the accompanying drawings are to be interpreted as illustrative and not in a limiting sense.

Having thus described my invention, I claim as new and desire to secure by Letters Patent:

1. A combination staple former and stapling apparatus comprising a movable head die and a plurality of means for moving in timed relation including wire feeding and rolling unit, a staple former portion for cutting and bending into U-shaped staples a wire fed by said unit, said former portion having a settor mounted on said head die, and a jaw head cooperating with said settor and head die for driving the staples through material positioned between the head die and the jaw head, said means also including a control cam for actuating said unit and the head die with the settor in relation to the jaw head, the latter carrying a presser member actuated by said cam for clinching driven staple ends, said presser member being constructed and arranged to be extended by said cam beyond the jaw head for cooperating in ejecting formed staples on failure to provide material to be fastened to the apparatus.

2. A combination staple former and stapling apparatus comprising a movable head die and a plurality of means for moving in timed relation including wire feeding and rolling unit, a staple former portion for cutting and bending into U-shaped staples a wire fed by said unit, said former portion having a settor mounted on said head die, and a jaw head cooperating with said settor and head die for driving the staples through material positioned between the head die and the jaw head, said means also including a control cam for actuating said unit and the head die with the settor in relation to the jaw head, the latter carrying a presser member

actuated by said cam for clinching driven staple ends, said jaw head having a slideway for said presser member, said slideway terminating in outwardly tapered sides for bending opposite end portions of said wire U-shaped structure toward each other on movement of the head die toward the jaw head, the cam control serving to extend said presser member beyond said slideway tapered sides for ejecting staples ineffectively formed.

3. A combination staple former and stapling apparatus comprising a movable head die and a plurality of means for moving in timed relation including wire feeding and rolling unit, a staple former portion for cutting and bending into U-shaped staples a wire fed by said unit, said former portion having a settor mounted on said head die, and a jaw head cooperating with said settor and head die for driving the staples through material positioned between the head die and the jaw head, said means also including a control cam for actuating said unit and the head die with the settor in relation to the jaw head, the latter carrying a presser member actuated by said cam for clinching driven staple ends, said control cam including a multi-groove cylinder in which the staple driving movements of said die head with the jaw head and the clinching by said presser member are constructed and arranged to take place within one tenth of each revolution of said cylinder.

4. A combination staple former and stapling apparatus comprising a movable head die and a plurality of means for moving in timed relation including wire feeding and rolling unit, a staple former portion for cutting and bending into U-shaped staples a wire fed by said unit, said former portion having a settor mounted on said head die, and a jaw head cooperating with said settor and head die for driving the staples through material portioned between the head die for driving the staples through material portioned between the head die and the jaw head, said means also including a control cam for actuating said unit and the head die with the settor in relation to the jaw head, the latter carrying a presser member actuated by said cam for clinching driven staple ends, said control cam constructed and arranged to provide movements for operating the wire feeding and rolling unit and staple former portion, said portion including slide members actuated through said cam, said wire feeding and rolling unit being mounted to reciprocate with one of the said slide members for drawing wire from a supply source.

5. A combination staple former and stapling apparatus comprising a movable head die and a plurality of means for moving in timed relation including wire feeding and rolling unit, a staple former portion for cutting and bending into U-shaped staples a wire fed by said unit, said former portion having a settor mounted on said head die, and a jaw head cooperating with said settor and head die for driving the staples through material positioned between the head die and jaw head, said means also including a control cam for actuating said unit and the head die with the settor in relation to the jaw head, the latter carrying a presser member actuated by said cam for clinching driven staple ends, said control cam comprising a multi-grooved cylinder constructed and arranged to provide movements

for operating the wire feeding and rolling unit and staple former portion, said portion including slide members actuated through said cylinder, said wire feeding unit being mounted to reciprocate with one of said slide members for drawing the wire from a supply source, said cam being constructed and arranged so that the staple driving movement of said settor and die head with the jaw head and the clinching by said presser member take place within one tenth of each revolution of the cylinder.

6. A combination staple former and stapling apparatus comprising a movable head die and a plurality of means for moving in timed relation including wire feeding and rolling unit, a staple former portion for cutting and bending into U-shaped staples a wire fed by said unit, said former portion having a settor mounted on said head die, and a jaw head cooperating with said settor and head die for driving the staples through material positioned between the head die and the jaw head, the latter carrying a presser member actuated by said cam for clinching driven staple ends, said jaw head having a slideway for said presser member, said slideway terminating in outwardly tapered sides for bending opposite end portions of the wire U-shaped structure toward each other on movement of the head die toward the jaw head, the cam control serving to extend said presser member beyond said slideway tapered sides for ejecting staples, ineffectively formed, said control cam including a multi-grooved cylinder constructed and arranged so that staple driving movements of said die head with the jaw head and clinching by said presser member occur with said die head and jaw head separated for the insertion of the material to be stapled therebetween for a greater part of each revolution of the cylinder.

7. A combination staple former and stapling apparatus comprising a movable head die and a plurality of means for moving in timed relation including wire feeding and rolling unit, a staple former portion for cutting and bending into U-shaped staples a wire fed by said unit, said former portion having a settor mounted on said head die, and a jaw head cooperating with said settor and head dies for driving the staples through material positioned between the head die and the jaw head, said means also including a control cam for actuating said unit and the head die with the settor in relation to the jaw head, the latter carrying a presser member actuated by said cam for clinching driven staple ends, said wire feeding and rolling unit being mounted for movement with the head die.
